CLAIM

The ornamental design for a board game, as shown and described.

DESCRIPTION

FIG. 1 is a perspective view of a board game; and, FIG. 2 is a top plan view thereof.

The broken lines shown in the drawing views are included for the purpose of showing environmental structure that forms no part of the claimed design.

1 Claim, 2 Drawing Sheets

Related U.S. Application Data

application No. 14/091,450, filed on Nov. 27, 2013,
now abandoned.
